Primary Examiner — Richard Kearney*Assistant Examiner* — Liv C Anderson(57) **CLAIM**

The ornamental design for a curtain light, as shown and described.

DESCRIPTION

FIG. 1 is a front, right and top perspective view of a curtain light showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of area 8 in FIG. 1; and,

FIG. 9 is an enlarged view of area 9 in FIG. 1.

The dash-dot-dash broken lines show the boundaries of the enlarged views and form no part of the claim thereof.
